UNITED STATES PATENT OFFICE.

AMALIE SCHAEFER, OF CHICAGO, ILLINOIS.

COMBINED WINDOW-CLEANER AND FIRE-ESCAPE.

SPECIFICATION forming part of Letters Patent No. 400,121, dated March 26, 1889.

Application filed November 9, 1888. Serial No. 290,369. (No model.)

To all whom it may concern:

Be it known that I, AMALIE SCHAEFER, a citizen of the United States, and a resident of Chicago, county of Cook, and State of Illinois, 5 have invented a new and useful Combined Window-Cleaner and Fire-Escape, of which the following is a specification.

My invention relates to devices to be employed in buildings for the purpose of enabling artisans to cleanse the windows from without, and also as a fire-escape, and has for its object to provide means for accomplishing this result.

My invention is illustrated in the accompanying drawings, wherein—

Figure 1 is a side view of my device. Fig. 2 is a perspective view. Fig. 3 is a view of a portion of the front of the building with my device in position. Fig. 4 is a detail of the 20 car. Fig. 5 is a detail of the mechanism for controlling the descent of the car.

Like parts are indicated by the same letter in all the figures.

A is the frame of the machine mounted on 25 the casters B B. Journaled on this frame is the windlass C, having the crank D at one end, together with the ratchet-wheel E and engaging-dog F, to lock the windows in position. Coiling upon the windlass are the ropes 30 G G, which pass over the pulleys H H on the hinged frame J, and thence to the eyes K K on the sides of the car L. This car is provided with a hinged door, M, whereby it may be entered at one side, such door being 35 thrown down when desired across the windowsill, so as to connect with the inside of the building. On the central portion of the windlass C is the friction-collar N, about which is placed the friction-strip O, one end of which 40 is secured to the movable block P on the rod R, which is secured to the standard S on the frame. The block P is forced upward by the spiral spring T. The other end of the strip O is rigidly secured at the point U. Pivoted 45 above the block is the lever V, having at one end an enlargement, the ends W W of which are at greater distances from the pivotal point than is the center of such end. Against the other end of this lever bears the spring X, 50 which tends to keep such lever in the position indicated in Fig. 5. From this end of the lever V proceeds the rope Y down into

keepers on the side of the car. The frame J is hinged to the frame A.

The use and operation of my invention are 55 as follows: When the device is out of use, the windlass is rotated by means of the crank D until the car is brought up into immediate proximity with the pulleys H H. The frame J is then inwardly swung, as shown in Fig. 1, 60 so that the frame J and car L will be virtually contained within the outlines of the frame A. When in this condition, the device may be moved within the building to any desired position.

When the device is to be employed as a 65 fire-escape or window-cleaner, or for other purposes where it is necessary to have access to the outside of the building or to descend along the same, the machine is moved in front 70 of a window, as shown in Fig. 1, and the frame J is turned on its hinges so that its pulley-supporting arms project from such window, as indicated in Fig. 3, and thus the car is permitted to descend.

To facilitate entrance into and exit from the car, the door M is turned down upon its 75 hinges until it lies across the window-sill. In this position the machine is ready for use, and the dog F is freed from the ratchet-wheel 80 E. The lever V is thrown over into the position indicated in Fig. 5 in full lines by the spring X, forces the block P downward, and thus applies the friction-strip O to the collar 85 N, so as to lock the windlass from motion and prevent the car and its contents from descending. If, now, the occupant of the car 90 desires to descend along the building, he will gently pull the rope Y until the lever V is in the position shown in dotted lines in Fig. 5, 95 whereupon, the grip of the friction-strip being loosened, the windlass will permit the car to descend. Should the occupant pull the rope Y too far, the lever V will be carried over into a position at an angle to that shown in the 95 dotted lines, whereupon the block P will be forced downwardly and the descent of the car will be stopped, so that it is only by holding the rope so as to keep the lever V in a certain fixed position that the car will be permitted to descend. This device thus operates as a safety release. The car can be drawn up by the use of the windlass.

Having thus described my invention, what I

claim, and desire to secure by Letters Patent, is as follows:

The combination of a vertically-moving car with a windlass and ropes therefrom to support the car, and a friction-strap about such windlass and connected at one end with a spring-actuated slide, and a pivoted lever which engages such slide at one end, and a rope secured to the other end of the lever, so

that by rocking such lever on its pivotal point the slide may be reciprocated to loosen or tighten the friction-belt, and thus control the rotation of the windlass.

AMALIE SCHAEFER.
